UNITED STATES PATENT OFFICE.

CHARLEY SHORT, OF COURTNEY, MISSOURI.

ROADBED-PLATE.

1,372,099.

Specification of Letters Patent. Patented Mar. 22, 1921.

Application filed December 10, 1920. Serial No. 429,706.

To all whom it may concern:

Be it known that I, CHARLEY SHORT, a citizen of the United States, residing at Courtney, in the county of Jackson and State of Missouri, have invented certain new and useful Improvements in Roadbed-Plates, of which the following is a specification.

My invention relates generally to road beds and while the invention is applicable to various kinds of roads it is intended more especially for use in the construction of railroads where rock ballast is employed. One object of the invention is to provide means for preventing the rock ballast from being washed out by rains or requiring frequent renewing as is now the case.

Another object is to prevent the ballast and the track from sinking into holes which may be washed in the dirt road bed underlying the plates, which latter constitute a bridge in such cases for supporting the ballast and the track.

Another object is to prevent earth from being washed up and intermingled with the ballast and forming a seed bed for the growth of weeds and other vegetation along the right of way.

A further object is to prevent water from collecting and freezing in the ballast and thereby upheaving and disintegrating the same.

With the above and other objects in view, reference will now be had to the accompanying drawing, in which:

Figure 1 is a plan view of two of the bed plates in assembled position, the dotted lines indicating how the plates may be swung out of line with one another, in rounding a curve in the road.

Fig. 2 is a cross section of a railroad track with the ballast resting upon the bed plates.

Fig. 3 is a perspective view of one of the plates.

Fig. 4 is a perspective view of a spike employed in connecting the plates together and in anchoring them to the underlying dirt road bed.

In carrying out the invention a metal bed plate 2 is employed, which is substantially rectangular in cross section, and provided at its side margins with upwardly extending flanges 4, which extend at an angle to conform with the sides of the ballast A, as disclosed on Fig. 2, and thus aid in hold-

ing said ballast in place. The plates 2 are tapered toward one end, so that the flanges 4 at the narrow end of one plate will fit into the flanges at the wide end of a companion plate.

The ends of the plates 2 have marginal notches 6 and central slots 8 through which spikes or anchors 10 are passed and driven into the underlying dirt road bed to hold the plates 2 in position. Drain holes 11 are provided in the plates through which rain may run off to prevent freezing in the ballast in cold weather.

Referring more particularly to the spikes or anchors 10, each consists of a broad head 12 and a body portion 14 having two broad surfaces 15, so that when a number of spikes are set at right angles to one another as shown on Fig. 2, they will prevent the plates 2 from creeping either longitudinally or laterally upon the underlying road bed.

In building a railroad, the dirt road bed is first graded and leveled in the ordinary manner. The plates 2 are then laid along said road bed, the narrow end of one plate fitting into the broad end of its companion where it is held by the anchors or spikes 10 which are passed through the notches 6 and slots 8 and driven into the underlying dirt road bed. In rounding a curve there is sufficient play between the ends of the plates 2 to enable them to be swung at an angle to each other on the central spikes 10, so that they may be laid to conform to such curve. The ballast A is then placed upon the plates 2, to receive the ties B and the rails C.

From the foregoing description it will be understood that I have provided plates which may be employed to advantage in the construction of permanent roads, and while I have shown the preferred form of the invention I reserve the right to make such changes and modifications as properly fall within the spirit and scope of the claims.

Having thus described my invention, what I claim and desire to secure by Letters Patent is:

1. A bed for road ballast, consisting of a plurality of plates adapted to be laid upon the road bed to support the ballast, and means for loosely connecting said plates together so that they may be arranged in alignment or adjusted at an angle to each other, for the purpose described.

2. A bed for ballast, consisting of a plurality of plates having drainage means and adapted to be laid upon the road bed to support the ballast, and flanges formed on the 5 sides of said plates to retain the ballast in place.

3. A bed plate smaller at one end than the other and provided with upwardly extending flanges at its sides, the ends of said

plate having notches and a central opening, 10 for the purpose described.

In testimony whereof I affix my signature, in the presence of two witnesses.

CHARLEY SHORT.
